CLAIM

The ornamental design for a toy table cover as shown and described.

DESCRIPTION

FIG. 1 is a front, right and top perspective view of a toy table cover, showing my design.

FIG. 2 is a rear, left and bottom perspective view thereof.

FIG. 3 is a rear, right and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is an enlarged view of detail 10 in FIG. 2; and,

FIG. 11 is an enlarged view of detail 11 in FIG. 3.

The dashed broken lines in the drawings depict stitching and form no part of the claimed design. The dot-dash broken lines in FIGS. 2, 3, 10, and 11 depict the boundaries of the enlargements and form no part of the claimed design.
